UNITED STATES PATENT OFFICE.

ALBERT P. BROOMEML, OF YORK, PENNSYLVANIA, ASSIGNOR TO VAPOR HEATING COMPANY, OF YORK, PENNSYLVANIA, A CORPORATION OF PENNSYLVANIA.

RECEIVER FOR VAPOR HEATING SYSTEMS.

No. 843,995.

Specification of Letters Patent.

Patented Feb. 12, 1907.

Application filed May 26, 1906. Serial No. 318,858.

To all whom it may concern:

Be it known that I, ALBERT P. BROOMEML, a citizen of the United States, residing at York, in the county of York, State of Pennsylvania, have invented certain new and useful Improvements in Receivers for Vapor Heating Systems, of which the following is a description, reference being had to the accompanying drawings, and to the letters and figures of reference marked thereon.

My invention relates to improvements in the receiver for steam-heating apparatus shown in Patent No. 717,335, December 30, 1902.

15 The objects of the invention are to prevent any possibility of the water overflowing from the receiver; to provide the lever of the relief-valve with an adjustable rod which may be set to be engaged by the ball, so as to open 20 the relief-valve at any desired pressure; to counterweight the ball at its bottom to keep its chain connection uppermost, and, finally, to cause any water from the relief-valve to overflow into the receiver, whence it will 25 return to the boiler. These objects I accomplish by the construction shown in the drawings, in which—

Figure 1 is a plan of my improved vapor-receiver. Fig. 2 is a section on line 2 2 of 30 Fig. 1. Fig. 3 is a section on line 3 3 of Fig. 1. Fig. 4 is a detail perspective of the elbow-coupling of the safety-valve.

B designates the receiver in the form of an upright cylinder, having an open upper end 35 upon which rests a centrally-apertured concave frame or spider b, having a lug b', entering a recess b² in the upper edge of the receiver to prevent the spider from turning. The lower contracted end of the receiver is 40 provided with a pipe B' for connection with the boiler at a point below the water-line for the return of the water of condensation or overflow from the safety-valve.

A is a chamber formed at the upper end of 45 the receiver and provided with the depending partition c, which terminates above the bottom of the chamber to cause the formation of a water seal. In the side of the chamber outside of the partition c is tapped the return-pipe D for the water of condensation 50 from the radiators, while into the top of this portion of the chamber is tapped the vent-

pipe E, which leads to the chimney, as in the patent above referred to.

F is the open top water-gage, in which the 55 water stands at a level, depending upon the slight pressure in the boiler, just as in the aforesaid patent.

G designates a suitable float in the receiver, carrying a chain g, extending up 60 through the guide-frame or spider b and thence to the furnace door or damper, (not shown,) as in the patent referred to. Within the bottom of the float is a weight g', which keeps the eye to which chain g is connected 65 always at the top.

On one side of the receiver is formed a relief-valve chamber H, opening into the receiver, this chamber being open at its top and bottom and formed with a lateral offset 70 portion H', in which is pivoted the outer end of the safety-valve lever i by means of a split key i⁵, the opposite end of which lever extends into the receiver above the float G, where it is provided with a slot i⁶. Extending 75 through the slot i⁶ is a vertically-adjustable rod G', provided with a series of apertures g², through any one of which and the slotted end of the lever is passed a split key or pin g³. The lower end of the valve-actuating rod G' is provided with an abutment or arm g⁵ in the form of a ring which lies in 80 the upward path of the ball-float G and affords a good contact-surface, and the upper end of the rod passes through a slot b³ in one 85 arm of the spider b.

The relief-valve I seats upon the upper end of an elbow-coupling I', which enters the lower open side of the chamber H, to which it is clamped by bolts h h, extending through 90 apertured ears i' on elbow I' and apertures in the flange h' of chamber H. The opposite end of the coupling or connection I' connects with the vapor or steam space of the boiler, as in the patent referred to. In the present 95 construction, however, should the boiler blow off water instead of steam the water will simply run into the receiver and back into the boiler instead of overflowing into the room in which the furnace is situated.

The stem i² of the valve I is slotted for the passage of the valve-actuating lever i, and to the reduced upper end of the valve-stem is secured a weight in the form of a ball I², hav-

ing a socket receiving the said reduced end, the two being secured together by a transverse pin i^3 . By pulling out the lever i , which is readily removable, the valve may be rotated and ground to its seat.

The ball works through the open upper end of the chamber H and in practice is made of some less expensive material than the valve itself, the latter being of brass, while the ball 10 is of cast-iron.

The valve is not actuated by steam-pressure in the boiler, but is opened only by the rise of the float.

The operation is substantially the same as in the aforesaid patent and may be briefly stated as follows: All of the return-pipes from the radiators lead to the chamber C , where the air is trapped and conducted to the chimney or other flue. When any pressure 15 exists in the boiler, the water will of course rise in the receiver until it balances the pressure in the boiler, and the rising of the float will cause the closing of the damper and usually prevent increase of pressure in the 20 boiler. Should the pressure in the boiler increase, however, the float will continue to rise and will raise the lever and cause it to open the relief-valve I , and should water blow off it will, as before described, not over 25 flow into the room, but will run into the receiver B . If it is desired to open the relief-valve at a very low pressure, the rod g is lowered near to the ball-float, and where 30 higher pressure is desired the rod will be raised the desired extent.

I do not restrict myself to the particular construction of parts shown, as the same may be varied without departing from the spirit of my invention.

35 Having thus described my invention, what I claim as new, and desire to secure by Letters Patent, is—

1. In a steam-heating apparatus, a receiver for the water of condensation from the radiators, a connection at the upper end of the receiver for the return water, a connection at the lower end of the receiver for returning the water to the boiler, a damper-actuating float in the receiver, a relief-valve 40 chamber at one side of and opening into the upper end of the receiver, and having a connection for the steam-space of the boiler, a relief-valve in the said chamber, and a lever for lifting the valve extending into the receiver for operation by said float.

2. In a steam-heating apparatus, a receiver for the water of condensation from the radiators, a connection at the upper end of the receiver for the return water, a connection at the lower end of the receiver for returning the water to the boiler, a damper-actuating float in the receiver, a relief-valve 50 chamber opening into the upper end of the receiver and having a connection with the steam-space of the boiler, a relief-valve in the 55 receiver for operation by said float.

chamber, a lever for lifting the valve, and a rod depending from the lever into the path of the said float.

3. In a steam-heating apparatus, a receiver for the water of condensation from the radiators, a connection at the upper end of the receiver for the return water, a connection at the lower end of the receiver for returning the water to the boiler, a float in the receiver provided with an upwardly-extending damper-actuating chain, a relief-valve chamber opening into the upper end of the receiver, and having a connection for the steam-space of the boiler, a relief-valve in the chamber, a weight secured to the upper side 70 of the valve, and a lever connected to the valve and extending into the receiver for operation by the float.

4. In a steam-heating apparatus, a receiver for the water of condensation from the radiators, a connection at the upper end of the receiver for the return water, a connection at the lower end of the receiver for returning the water to the boiler, a float in the receiver having a damper-actuating chain, a relief-valve having a connection for the steam-space of the boiler, and provided with an operating-lever extending into the receiver, an adjustable rod depending from the inner end of the lever, and having an abutment at its lower end in the upward path of the float.

5. In a steam-heating apparatus, a receiver for the water of condensation from the radiators, a connection at the upper end of the receiver for the return water, a connection at the lower end of the receiver for returning the water to the boiler, a damper-actuating float in the receiver, a relief-valve chamber opening into the upper end of the receiver and open at its top and bottom, an elbow-coupling to connect with the steam-space of the boiler, and entering the lower open side of said chamber, means for securing said elbow to the chamber, a relief-valve seating on the upper end of the elbow, a lever in the chamber connected to said valve and at its free end entering the receiver in operative relation to the float.

6. In a steam-heating apparatus, a receiver for the water of condensation from the radiators, having a trap-chamber at its upper end, a return-pipe connection for said chamber, a vent-pipe connection for the top of said chamber, a connection from the lower end of the receiver to return the water to the boiler, a float in the receiver having a damper-actuating chain and weighted at its lower end to keep the chain connection on top, a relief-valve having a boiler connection 110 and a valve-operating lever entering the receiver for operation by the float.

7. The combination with the relief valve-chamber having a seat at its lower end and open at its top and side, of a valve seated on 115 120 125 130

the said seat and provided with a weighted extension extending up through the top opening and an actuating-lever removably connected to the valve, whereby on removing 5 the lever the valve may be rotated on its seat by means of its projecting extension.

8. In a steam-heating apparatus, a receiver for the water of condensation from the radiators, a connection at the upper end of the receiver for the return water, a connection at the lower end of the receiver for returning the water to the boiler, a damper-actuating float in the receiver, a relief-valve for the steam-space of the boiler, a lever extending 5 from the valve into the receiver, a vertically-adjustable rod depending from the inner end of the lever and having a lateral abutment at its lower end in the path of the float.
9. In a steam-heating apparatus, a receiver for the water of condensation from the

radiators, a connection at the upper end of the receiver for the return water, a connection at the lower end of the receiver for returning the water to the boiler, a guide-frame or spider on the upper open end of the receiver, and having an interlocking connection therewith, a damper-actuating float in the receiver, a relief-valve connected with the steam-space of the boiler, a lever for lifting the valve extending into the receiver, a vertical rod adjustably connected to said lever, guided at its upper end in the guide-frame, or spider, and having a ring-like abutment at its lower end in the path of the float. 25 30 35

In testimony whereof I affix my signature in presence of two witnesses.

ALBERT P. BROOMEELL.
